UNITED STATES PATENT OFFICE.

GEORGE WASHINGTON HADESTY, OF DRIFTON, PENNSYLVANIA.

COMBINED WEATHER-STRIP AND DOOR-STOP.

SPECIFICATION forming part of Letters Patent No. 319,490, dated June 9, 1885.

Application filed February 16, 1885. (No model.)

To all whom it may concern:

Be it known that I, GEORGE W. HADESTY, a citizen of the United States, residing at Drifton, in the county of Luzerne and State of Pennsylvania, have invented a new and useful Improvement in Combined Weather-Strip and Door-Stop, of which the following is a specification, reference being had to the accompanying drawings.

- 10 This invention relates to weather-strips, and more particularly to that class of the same in which a door stop or check is combined therewith, to serve as a handle in raising and lowering the same.
- 15 The invention consists in the improved construction and novel combination of parts, as will be hereinafter set forth, and pointed out in the claim.

In the drawings, Figure 1 is a detail view 20 of a portion of a door, showing my improvement applied thereto. Fig. 2 is a longitudinal vertical section of the same, and Fig. 3 is a transverse vertical section.

In the accompanying drawings, in which 25 like letters of reference indicate corresponding parts in all the figures, A represents a portion of a door, which is provided at its lower end or edge with a channel or recess, a, extending its entire width, and communicating with 30 said channel or recess at a point midway between its ends is a vertical recess or channel, b.

Upon the front face or side of the door, adjacent to the lower end thereof and directly over the channel or recess b, is secured an outwardly-extending plate or bracket, B, which is slotted at its outer end, and pivoted in said bracket or plate is a handle or lever, C, carrying at its outer end an elastic cushion—such as cork, rubber, &c. The lower end of the 40 pivoted handle or lever C extends into the groove or channel b, and is pivoted at said lower end to the upper end of an arm, D, which in turn is rigidly connected at its lower end with a pipe or tube, E, fitted in the recess 45 or channel a, and fitted in said pipe or tube, and having its edge projecting through a slot

in the said pipe or tube, is a strip of rubber or like material, which, when the pipe or tube is lowered by means of the pivoted lever or handle, serves to close the space between the 50 door and the threshold-strip, and thus prevent the entrance of snow and rain and, to a greater or less extent, cold air.

When it is not desired to use the weather-strip, the same may be raised by lowering the 55 pivoted lever or handle, which raises the pipe or tube and the strip of rubber up into the recess or channel a. When the door is opened or swung back, the pivoted lever carrying the elastic cushion in it strikes against the base 60 or wash board and serves as a stop, thus preventing the plastering from being broken, as is ordinarily the case when a stop is not employed.

Many advantages are derived from the employment of my invention, as, for instance, in warm weather, when it is not necessary to employ a weather-strip, the same may be raised from engagement with the floor or threshold-strip up into the groove or channel, and yet 70 the stop remains in position for operation.

The above-described improvement is simple in its construction, may be manufactured and supplied at a slight cost, and is positive and effective in its operation.

Having fully described my invention, what I claim as new, and desire to secure by Letters Patent, is—

The combination, with the door, channeled or recessed as described, and the lever C, pivoted to the door, of the arm D, pivoted to the inner end of the lever, a pipe or tube, E, attached to the lower end of the arm, and a weather-strip fitted in a slot of the tube or pipe, as and for the purpose set forth.

In testimony that I claim the foregoing as my own I have hereto affixed my signature in presence of two witnesses.

GEORGE WASHINGTON HADESTY.

Witnesses:

JOHN WHAREN,
ISAIAH KLINE.
